CARL G. SWEBILIUS, OF NEW HAVEN, CONNECTICUT, ASSIGNOR, BY MESNE ASSIGNMENTS, TO THE MARLIN FIREARMS CORPORATION, OF NEW HAVEN, CONNECTICUT, A CORPORATION OF DELAWARE.

FIREARM.

Application filed May 20, 1920. Serial No. 333,016.

This invention relates to firearms of the automatic type and pertains more particularly to firing-control mechanisms for such guns.

5 The subject matter of this application is disclosed partly in my application Serial No. 272,846, filed January 24, 1919, and partly in my application Serial No. 297,201, filed May 15, 1919, but claimed in neither.

10 In certain types of automatic firearms the forward movement of the breech mechanism is effective to chamber a cartridge and explode the same immediately thereafter. In this type of guns the breech mechanism is usually retained in the rear portion of the receiver by a sear or the like which is moved from its retaining position to release the breech mechanism by a manually-operated trigger. It is to guns of this character that 20 my invention is particularly applicable.

In such guns as these, more especially if they are intended for use in warfare, it is desirable to provide means for controlling the conditions of firing thereof whereby the 25 gun may be operated automatically or semi-automatically or may be locked against operation. To accomplish this I have arranged a pivotally-mounted sear in the receiver, which sear is adapted to engage the breech mechanism when it is in the rear portion of the receiver and to retain it in such position. Operatively associated with the 30 sear is a spring-pressed reciprocatively-mounted trigger. Interposed between the trigger and the sear is a spring which normally maintains the sear in position to engage the breech mechanism. The trigger and sear are provided with coacting means whereby movement of the trigger in one direction a predetermined distance is effective to move the sear out of breech-mechanism-engaging position, and further movement of the trigger in the same direction allows the sear to resume its normal position. Furthermore, the arrangement of said means is such during the return of the trigger to its original position after the sear has been oscillated, the sear remains in its normal position. In connection with the trigger are provided means regulating the path of reciprocation of the trigger. This means may be set to lock the trigger in its normal position, may be set to allow only sufficient movement of the trigger to move the sear

out of engaging position or may be set to 55 allow the trigger to be drawn the full limit of its path. The first arrangement of said means prevents the firing of the gun; the second arrangement allows full automatic or continuous firing of the gun since, as 60 long as pressure is exerted on the trigger, the sear is maintained out of position to engage the breech mechanism; the third arrangement provides for single-shot firing since the trigger must be released and then 65 again pulled before the sear can be again disengaged from the breech mechanism. The regulating means is so arranged that the change from volley-firing position to single-shot position and vice versa may be 70 easily made, but said means cannot be accidentally moved into safety position, although the change from safety position to either of the other two positions may be 75 readily made.

Referring now to the drawings,

Fig. 1 is a longitudinal section through the receiver with the elements of the gun in cocked position, part of the elements being 80 in elevation;

Fig. 2 is a section on line 2—2 of Fig. 1;
Fig. 3 is a section on line 3—3 of Fig. 1;

Fig. 4 is a view similar to Fig. 1 of a modification;

Fig. 5 is a section on line 5—5 of Fig. 4;

Fig. 6 is a fragmentary inverted plan view, partly broken away, of said modification;

Fig. 7 is a view showing the firing control adjustment of said modified form.

In the receiver 1 is reciprocatively mounted the breech bolt 2 which is operatively connected to the rear end 3 of the action slide 3^a. The bottom portion of the action slide is provided with a shoulder 4 which is adapted to be engaged by the sear 5 to retain the breech mechanism at the rear end of the receiver when the gun is cocked.

The bottom wall of the receiver is preferably a plate 6 which has tongues 7 engaged in grooves 8 in the outer faces of the side walls of the receiver and which may be removed from the receiver by a sliding movement. Extending downwardly from the plate is a rib 9, the rear portion of which is cut out as at 10. In the plate 6 and extending into the rib 9 is a groove 11, the

forward end of which is extended downwardly to form a well 12. The upper portion of this groove is of greater width than the lower portion thereof, thus providing 5 the shoulders 13 extending longitudinally of the groove. In the groove is pivotally mounted, by means of the removable pin 14, the sear 5, having legs 15 at its forward end adapted to engage the shoulders 13 in 10 the groove 11 to limit the downward movement of the forward end of the sear. Reciprocatively mounted in the groove 11 and directly below the sear 5, is the trigger 16 having at its forward end the head 17 extending down into the well 12, the upper front portion of the head being reduced sufficiently to extend between the legs 15 of the sear 5, and having at its rear end the finger piece 18 extending into the cut-out 15 portion 10 of the rib 9. Carried by the sear 5 is a wire spring 18^a which bears against the trigger 16 and serves to normally hold the rear end of the sear in position to engage the shoulder 4 on the rear end of the action 20 slide, the contact of the legs 15 with the shoulder 13 preventing the engagement of the front ends of the trigger 16 and sear 5. On the under surface of the front end of the sear is a projection having the face 19 25 oblique to the surface of the sear and the face 20 perpendicular thereto. This projection is preferably formed by cutting two transverse notches in the under surface of the sear. In the head 17 is a recess in which 30 is pivotally mounted a dog 21, an oblique-faced portion 22 of which projects above the upper surface of the trigger 16 sufficiently to be in alinement with the projection on the sear. This dog is normally held in 35 the position shown in Fig. 1 by the spring 23, but may be rotated rearwardly so that the dog is wholly within the socket. The trigger is normally held in its forward position by means of the stud 24 seated in the 40 aperture 25 at the rear end of the groove 11, which stud bears against the spring 26 seated in the socket 27, in the rear end of the trigger. Extending through the walls of the well 12 is a transverse elliptical cut in 45 which is reciprocatively mounted a slide 28 having in its forward edge a recess 29, the inner portion of which is of sufficient width to receive the reduced inner end of the head 17 of the trigger, and the walls of which 50 recess are cut away to provide the shoulders 30 and 31 at different distances from the bottom thereof. On the rear edge of the slide are cut the notches 32, 33 and 34, the adjacent walls of the notches 32 and 33 being oblique to the edge of the slide, while the wall of the notch 33 adjacent the notch 34 is approximately perpendicular to the edge of the slide, and the wall of the notch 34 adjacent the notch 33 is oblique to the 55 edge of the slide. Reciprocatively mounted 60

in the well 12 below the slide 28 and the head 17 is a semicircular rod 35 which extends through a bore in the front portion of the rib 9. The forward end of this rod is provided with a cylindrical head 36 and carries at its rear end a projection 37, the edge of which is adapted to engage in any of the notches 32, 33 and 34. One of the faces of this projection is oblique and the other perpendicular to the edge of the slide 28. 70 The rod 35 is normally held with the edge of the projection 37 in engagement with the slide 28 by the spring 38. 75

To lock the gun in safety the rod 35 is pushed rearwardly and the slide 28 is moved 80 to bring the shoulder 31 in position to be engaged by the head 17 of the trigger. This shoulder is so arranged on the slide as to prevent appreciable movement of the trigger. To set the gun for single-shot firing 85 the slide is moved to bring the narrow portion of the recess 29 in alinement with the head 17. The trigger may now be drawn back the full limit of its throw. 90

During the first part of the rearward movement of the trigger the contact of the oblique faces 19 and 22 of the sear 5 and dog 21 respectively lifts the front end of the sear and disengages the rear end thereof from the shoulder 4, thereby allowing the 95 breech mechanism to move forward and fire the gun. Further rearward movement of the trigger disengages the dog from the projection on the sear and allows the sear to return to normal position under the influence of the spring 18 to be ready to engage the shoulder 4 when the breech mechanism is returned to the rear of the receiver. A release of the pressure on the trigger will now allow it to return to its original position under the influence of the spring 26. During the return movement of the trigger the dog, when its perpendicular face contacts with the face 20, rotates about its axis into its recess until the trigger reaches its forward 100 position when the dog is free to resume its normal position under the influence of the spring 23. Since the time which is consumed during a reciprocation of the breech mechanism is only a very small fraction of a 105 second, the sear is again engaged with the shoulder after being tripped before it is possible for the trigger to be returned to its normal position. The fact that a complete reciprocation of the trigger is necessary for each tripping of the sear results in the firing of only a single shot for each pull of the trigger. The gun may be set for automatic 110 firing by moving the slide 28 to bring the shoulder 30 into position to engage the head 17. This shoulder is so arranged on the slide that the trigger can be moved rearwardly only enough to lift the forward end of the sear but not enough to allow the sear to resume normal position. Thus a pull on 115

the trigger disengages the sear from the shoulder 4 and maintains it out of shoulder-engaging position so long as pressure is exerted on the trigger. This allows the breech mechanism to reciprocate uninterruptedly under the influence of the force exerted by the explosion and the action spring.

The slide 28 is maintained in any one of its three positions by the engagement of the projection 37 in one of the notches 32, 33 and 34. The arrangement of the oblique and perpendicular faces of the notches and the projection 37 is such that the slide 28 can be moved from safety position to single-shot or automatic-firing positions or from single-shot position to automatic-firing position, and vice versa merely by pressing the slide in the proper direction but to move the slide into safety position the rod 35 must first be pushed rearwardly. This feature is of importance if the gun is to be used in warfare. The notches and projection may, however, be so formed that it will be necessary to push back the rod 35 to change the conditions of firing from one to the other.

The sear, trigger, slide and rod may be removed from the plate 6 by removing the pin 14 and lifting out the sear. The stud 24 may then be forced out of the aperture until its rear end is flush with the rear wall of the groove 11, after which the trigger may be removed from the groove. The rod 35 is then pushed rearwardly against the action of the spring 38 sufficiently to allow the slide 28 to be removed, after which the rod itself may be withdrawn through the bore.

In the modification disclosed in Figs. 4 to 7 inclusive, the forward end of the sear 5 is forked to provide the arms 41 between which extends a pin 42 which is adapted to be engaged by the dog 21. Cut in the bottom of the well 12 is a curved slot, through which extends a pin 43 carried by the resilient lever 44 pivotally mounted on the rib 9, which pin is adapted to assume any of the three positions indicated in dotted lines in Fig. 6. On the end of the lever 44 is a stud 45 which is adapted to seat in any of the sockets 46 on the rib 9 to hold the lever 44 with the pin 43 in any of the three aforementioned positions. On the bottom of the head 17 are the two lugs 47 and 48 of different lengths which are spaced from each other and which are adapted to engage the pin 43. To lock the gun in safety the lever 44 is arranged with the pin 43 in position to be engaged by the longer lug 47, thus preventing movement of the trigger. For single-shot firing the lever 44 is positioned with the pin 43 clear of either lug. This allows the trigger to be drawn back its full limit, which movement is effective to disengage the sear and then allow it to return to normal position. To set the gun for automatic firing the pin 43 is located in position to be engaged by the

lug 48. The trigger is then capable of movement only enough to disengage the sear and not enough to allow it to return to normal position until the pressure on the trigger is released, thus allowing free and continued reciprocation of the breech mechanism.

It is understood, of course, that the particular device shown and described in the present application illustrates merely a preferred form of construction and an arrangement of parts, which, it has been found, will successfully carry out the principles of my invention, and that various changes and modifications of details may easily be made without departing from the spirit of my invention as defined in the appended claims.

What I claim is:

1. In an automatic gun, a substantially straight sear pivoted intermediate its ends, a trigger mounted adjacent said sear for reciprocation along a path substantially parallel to said sear, coacting means on said sear and trigger whereby reciprocation of said trigger oscillates said sear, and a spring interposed between said sear and trigger. 90

2. In a firearm, a reciprocatively-mounted trigger, a sear pivotally mounted adjacent said trigger and substantially coextensive therewith, means for normally maintaining said sear and trigger in substantially parallel relation to each other, coacting means on said trigger and sear whereby the sear is first moved from and then allowed to return to its normal position upon the continuous movement of the trigger from its normal position to the opposite end of its path of reciprocation, and adjustable means for limiting the reciprocation of the trigger. 100

3. In a firearm, a reciprocatively-mounted trigger, a sear pivotally mounted adjacent said trigger and substantially coextensive therewith, means for normally maintaining said sear and trigger in substantially parallel relation to each other, coacting means on said trigger and sear whereby the sear is first moved from and then allowed to return to its normal position upon the continuous movement of the trigger from its normal position to the opposite end of its path of reciprocation, and is left undisturbed upon the return of the trigger to its normal position, and adjustable means for limiting the reciprocation of the trigger. 110

4. In an automatic gun, a firing-control unit comprising a plate, a sear pivotally mounted therein, a trigger mounted in said plate for reciprocation only, and means carried by said plate for regulating the sliding movement of said trigger. 120

5. In a firearm, a pivotally mounted sear, arms at one end of said sear, a pin connecting said arms, a sliding trigger located adjacent said sear, and a cam surface on said trigger to engage said pin. 125

6. In a firearm, a pivotally mounted sear, 130

arms at one end of the sear, a pin connecting said arms, a sliding trigger located adjacent said sear, a dog pivotally mounted on said trigger, and a cam surface on said 5 dog to engage said pin.

7. In a firearm, a pivotally mounted sear, arms at one end of said sear, a pin connecting said arms, a sliding trigger located adjacent said sear, a dog pivotally mounted on 10 said trigger, a cam surface on the trigger adapted to engage said pin, and means to regulate the movement of said trigger.

8. In a firearm, a pivotally mounted sear, a trigger slidably associated therewith, 15 means on the trigger to operate the sear, lugs on the trigger, and a pivoted lever having a pin adapted to engage said lugs.

9. In a firearm, a pivotally mounted sear, arms at one end of said sear, a pin connecting 20 these arms, a sliding trigger located below said sear, a dog pivotally mounted on said trigger, a cam surface on said dog to engage said pin, lugs on the trigger, a pivoted lever, and means thereon to engage said 25 lugs.

10. In a firearm, a pivotally mounted sear, arms at one end of the sear, a pin connecting these arms, a sliding trigger located below the sear, a dog pivotally mounted on 20 the trigger, resilient means to normally hold the dog in one position, a cam surface on the

dog to engage said pin, lugs on the trigger, a pivoted lever, and means thereon to engage said lugs.

11. In a firearm, a reciprocatively mounted 35 trigger, a plurality of lugs thereon, a pivoted lever, and means thereon for engaging said lugs.

12. In a firearm, a trigger, a sear, a yielding pawl on said trigger adapted to engage 40 said sear, a pivoted member, and means on said trigger and pivoted member for varying the extent of movement of the trigger.

13. In a firearm, a trigger, a sear, a yielding pawl on said trigger adapted to engage 45 said sear, a pivoted member, and means on said trigger and pivoted member for varying the stroke of the trigger.

14. In a firearm, a trigger, a sear, a yielding pawl on said trigger adapted to engage 50 said sear, a pivoted member, and a plurality of projections on said trigger and pivoted member adapted to engage each other to vary the stroke of said trigger.

15. In a firearm, a trigger, a sear, a yielding pawl on said trigger adapted to engage 55 said sear, a pivoted member, a plurality of projections on said trigger, and a single projection on said pivoted member adapted to be engaged by said other projections whereby the stroke of said trigger may be varied. 60

CARL G. SWEBILIUS.
